FORK OR OTHER ARTICLE OF FLATWARE

Carl Gunnar Åkerlind, Stockholm, Sweden, assignor to Aktiebolaget Nilsson & Johansson, Stockholm, Sweden

Application July 24, 1946, Serial No. 131,878
In Sweden May 14, 1946

Term of patent 3½ years

(Cl. D54—12)

To all whom it may concern:

Be it known that I, Carl Gunnar Åkerlind, a subject of the King of Sweden, residing at Hornsgatan 160, Stockholm, Sweden, have invented a new, original, and ornamental Design for a Fork or Other Article of Flatware, of which the following is a specification, reference being had to the accompanying drawing, forming part thereof.

Fig. 1 is a front elevation of a fork or other article of flatware, showing my new design,

Fig. 2 is a side elevation of the same,

Figs. 3 and 4 are, respectively, sectional views on lines 3—3 and 4—4 on Fig. 1.

My design for a fork is characterized by the side members of the handle being waved unsymmetrically to each other, with one flower on the upper body of the handle and another flower

slightly below within a wave-like, leaf-shaped element of ornamentation, all as illustrated on the drawing.

I claim:

The ornamental design for a fork or other article of flatware, as shown and described.

CARL GUNNAR ÅKERLIND.
